UNITED STATES PATENT OFFICE.

CHARLES THOMAS MASON, OF SUMTER, SOUTH CAROLINA, ASSIGNOR TO SUMTER ELECTRICAL COMPANY, A CORPORATION OF SOUTH CAROLINA.

IGNITION-DYNAMO.

1,105,361.

Specification of Letters Patent. Patented July 28, 1914.

Application filed May 10, 1912. Serial No. 696,487.

To all whom it may concern:

Be it known that I, CHARLES THOMAS MASON, a citizen of the United States, residing at Sumter, in the county of Sumter 5 and State of South Carolina, have invented certain new and useful Improvements in Ignition-DYNAMOS, of which the following is a specification, reference being had to the accompanying drawings.

10 My invention relates to ignition dynamos, and particularly to that class of ignition dynamos commonly termed high tension magnetos such as used for igniting the charge in internal combustion engines, and

15 consists of certain improvements as herein-after specified, embodying the principle of operation disclosed in my application for Letters Patent filed April 23rd, 1912, Serial Number 692,754.

20 The objects of my invention are, to provide a machine of increased efficiency in which the spark is of the same intensity in either the advance or retard position, in which the various parts are easily constructed and assembled, all sliding circuit contacts being eliminated, and the elimination of the multiplicity of circuit connections heretofore necessary between the primary winding, the condenser, and the circuit breaker, in machines having stationary

25 windings.

In the accompanying drawings Figure 1 is a sectional view of a magneto embodying my invention, Fig. 2 a sectional view at right angles to the position shown in Fig. 1, and Fig. 3 a schematic diagram of the circuit connections.

The same letters of reference denote the same parts wherever they are shown.

40 1 denotes a base of non-magnetic material having upwardly projecting portions 2 and 3 which support the U shaped permanent magnet 4. The polar extremities of 4 have suitable apertures through which project the

45 sleeve bushings 5 and 6 of the end plates 7 and 8 which find bearing in the supports 2 and 3, but which are in close contact with the inner polar surfaces of the magnet 4. Placed between the end plates 7 and 8 is a

50 group of laminae shown at 9 forming a core for the windings 10 and 11 which may be placed one on top of the other or in any other suitable inductive relation. The continuous path for the magnetic flux from pole to pole 55 of the magnet 4 is broken by means of the

brass or other non-magnetic rings indicated at 12 and 13.

It will be observed that the laminations, end plates, and rings just described form a field structure which is free to move in the 60 bearings in the supports 2 and 3. This structure forms a housing, the inner portions of the laminations being cut away to leave oppositely positioned pole shoes indicated at 14 and 15. Attached to the field, 65 structure and movable therewith is the condenser 16 which may be connected to the windings and, as it is movable with said windings, all sliding contacts are eliminated.

In bearings formed in the sleeve bushings 70 on the end plates 7 and 8 are placed the shafts 17 and 18 of a rotor consisting of the magnetic elements 19 and 20 separated by a block of non-magnetic material 21. It will be noted that the members 19 and 20 form 75 movable polar extensions to the polar extremities of the magnet 4 and always maintain the same polarity in relation to said magnet irrespective of their position in relation to same. This feature of design is 80 more fully described and claimed in the application for Letters Patent hereinbefore mentioned.

Attached to one of the shafts is the cam 22, and attached to the corresponding end plate 85 by ring 23 is the circuit interrupter mechanism 24, 25 and 26. As the rotor shafts are moved cam 22 will move ball or roller 24, thereby separating the contact spring 25 from stationary contact 26. As the interrupter mechanism 23 is attached to and movable with the field structure, and this can be partially rotated in relation to the polar extremities of the magnet, it is thereby possible to advance or retard the time of the 90 spark while the intensity of the spark remains the same because the intensity of the magnetic flux remains the same for all positions of the field.

By reference to Fig. 3 a suitable form of 100 circuit connection will be seen. One side each of the primary and secondary windings 10—11 is connected to the frame of the machine as is also one of the circuit interrupter contacts 26. One side of the spark plug or other igniting device is connected to the frame of the engine which, of course, is in electrical connection with the frame of the magneto through the base of same. A conductor 27 connects the remaining side of the 105 110

primary winding and one side of the condenser 16 to the insulated interrupter contact 25. The other side of the condenser is connected to frame and 26. The wire 28 is 5 the usual high tension cable direct to the insulated terminal of the spark plug.

It will be observed from the foregoing that I eliminate all brushes, commutators or collecting rings and sliding contacts of any 10 nature, which is of great advantage especially in connection with the primary circuit of a magneto of this type. I also eliminate the necessity of laminæ in the movable rotor, that the total number of parts heretofore 15 necessary have been greatly reduced and their construction materially simplified. The construction of the field structure is such that the windings placed thereon may be readily insulated and the condenser may be 20 of ample size, whereas heretofore it was necessary to restrict the size of the condenser as much as possible, owing to the fact that to insure the best results the condenser was commonly mounted into the armature structure. 25

While I have shown a machine in which the rotor is adapted to be revolved, it is obvious that the same may be oscillated and the same effect produced. And while I have 30 shown a magneto equipped with two windings distinct from each other except where connected to the frame of the magneto, it is obvious that a single winding or a plurality of windings may be employed, and that the 35 shape of the core on which these are placed may be modified within wide limits—for instance, the core may be round or oval with the pole shoes extending toward the center from opposite points, the windings being 40 placed on opposite sides of the pole shoes.

The operation of a magneto as just described is as follows:—Considering the left-hand pole of the magnet 4 to be of N polarity polar extension 19 is of the same polarity 45 and remains so, regardless of any position in which it may be. The rotor as a whole, being in the position shown in Fig. 2, the magnetic flux will flow from the N pole of the magnet through the polar extension 19 to 50 the pole shoe 15 as soon as the rotor is revolved to the left, then through the laminated core 9 to pole shoe 14 to polar extension 20 to the S side of the magnet. As the rotor revolves the polar extensions bridge 55 the upper and lower gaps between the pole shoes and magnetically short circuit the field structure. A further revolution of the armature will cause a reversal of the magnetic flux. In synchronism with the peak of 60 the current produced in the winding by reason of the change in the magnetic flux, the interrupter mechanism is operated by the cam 22 thereby opening the short circuit around the primary winding which causes 65 a flow of current in the secondary winding

thereby producing the spark at the plug. It will be observed that only two peaks of current are produced per revolution and for one or two cylinder engines no distributor is necessary in the secondary circuit, although it is obvious one may be employed in the case of multicylinder engines. 70

I claim:

1. In a dynamo for ignition, a magnet, rotatable polar extensions on said magnet 75 having a permanent N and S polarity irrespective of their movements in relation to the magnet, curved radial faces on said polar extensions, an adjustable field structure, windings on said field structure, curved faces 80 on said field structure adjacent the radial faces of said polar extensions, and a condenser carried by said field structure.

2. In a dynamo for ignition, a substantially U shaped magnet, movable polar extensions on the extremities thereof and in contact therewith, a support for said extensions, means interposed between said extensions whereby the motion of one is transmitted to the other, a field structure projecting 85 partly into the bend of said magnet, windings on said structure, and a condenser carried thereby. 90

3. In a dynamo for ignition, a substantial U shaped magnet, a rotor formed of 95 polar extensions on said magnet, said rotor consisting of supporting shafts and magnetic conducting elements formed integral therewith; said elements being joined together in the center by a non-magnetic 100 block, and an adjustable field structure having two or more windings and carrying interrupter contacts and a condenser.

4. In a dynamo for ignition, a magnet having poles and rotatable polar extensions 105 having a permanent N and S polarity, a shaft for said extensions, supports for said shaft, a plurality of windings, a core for said windings, extensions on said core forming pole shoes adjacent the path of travel of 110 said polar extensions of said magnet, a condenser carried by said core and connected to one of the windings, and means for varying the angular position of said pole shoes with respect to said magnet poles. 115

5. In a dynamo for ignition, a base, a magnet fixed to said base, extensions on said base forming bearings, a core structure carried in said bearings, two windings on said core, a condenser carried by said core structure, and means interposed between said magnet and core structure for varying the magnetic flux between them, said means comprising polar extensions on said magnet having definite N and S polarities irrespective 120 of their positions in relation to said magnet. 125

6. In a dynamo for ignition, a base having vertical projecting portions forming magnet supports, a magnet secured to said supports, bearings in said supports, a core 130

structure movably supported in said bearings, a rotor and shaft therefor movably supported in said core structure, polar extensions for said magnet carried by said shaft and having definite N and S polarity, a cam on said shaft, interrupter mechanism carried by said core structure and operated by said cam, windings on said core structure, and a condenser carried thereby.

7. In a dynamo for ignition, a base, a magnet carried thereby, a field structure forming a core and having its field opening at substantially right angles to the poles of said magnet, movable polar extensions for 15 said magnet projecting into said field opening, supports for said field structure whereby its angular position may be varied with respect to the magnet poles, windings on said field structure, and a condenser carried 20 thereby.

8. In a dynamo for ignition, a base, a substantially U-shaped magnet carried thereby, openings through the polar extremities of said magnet, vertical extensions on said 25 base, bearings in said vertical extensions coaxial with the openings of said magnet, magnetic end plates supported in said bearings, a laminated core structure between said end plates and supported thereby, extensions on 30 said core structure forming pole shoes, windings on said core structure, a condenser connected to one of said windings, bearings in said end plates, movable polar extensions for said magnet supported in said end plate 35 bearings, non-magnetic material between said polar extensions whereby motion may be transmitted between them, interrupter mechanism carried by one end plate and movable therewith, and a cam carried by the 40 shaft of one of said polar extensions for operating the interrupter contacts.

9. A magneto electric machine comprising a U-shaped permanent magnet structure, a base member of non-magnetic material embracing the poles of said magnet structure, a rotary inductor embraced by said magnet poles in an end-wise position and having stub shafts which project through apertures in said field magnet structure and are journaled in bearings carried on said base.

10. A magneto electric machine comprising a permanent field magnet structure, said structure having transversely aligned apertures in its poles, a rotary inductor embraced in an end-wise position by the poles of said magnet, and bearings therefor supported laterally of said magnet poles and supporting the shaft of said rotary inductor free from the interior walls of said aperture.

11. A magneto electric machine comprising a U-shaped permanent magnet, a base of non-magnetic material upon which the magnet is mounted, a rotary inductor embraced by the poles of said magnet in end-wise position and having stub shafts which

project through apertures in the poles of said magnet, lateral bearing members supported from said base and in turn supporting said rotary inductor free from the side walls of said apertures.

12. A magneto electric machine comprising a U-shaped permanent magnet having an aperture in each pole on a line extending transversely thereof, an armature structure embraced by said poles and comprising pole 75 shoes, a non-magnetic frame rigidly connecting them together, and end plates of magnetic material supporting said frame, lying laterally adjacent the inner cheeks of said field poles and having journal sleeve bushings projecting through said apertures, and a rotor located between said pole shoes, embraced by the poles of said field magnet in end-wise position and having stub shafts which project through said journal bushings 80 85 of the armature structure.

13. A magneto electric machine comprising a U-shaped permanent magnet, a rotor embraced by the poles of said magnet in an end-wise position, adapted to rotate in said 90 position and having inductors of magnetic material having an unbroken magnetic contact with said poles, an armature structure comprising a pair of spaced pole shoes embracing said rotor, and a frame of non-magnetic material spacing said pole shoes and supporting the same from the axis of said rotor whereby the same may be freely adjusted angularly thereabout.

14. A magneto electric machine comprising a U-shaped permanent magnet, a rotor journaled on an axis transversely of said magnet poles and having inductor members in magnetic contact with the poles of said magnet whereby the same are of permanent 105 north and south polarity, an armature structure in juxtaposition to said inductor and comprising pole shoes adjacent the path of rotation of said inductor, and a frame of non-magnetic material by which said pole 110 shoes are spaced apart, and through which said armature structure is adjustably supported from the axis of said rotor, whereby the same may be moved angularly thereabout.

15. A magneto electric machine comprising a U-shaped permanent magnet, a rotor journaled in end-wise position between the poles of said magnet and comprising a central block of non-magnetic material, angular segments of magnetic material constituting inductor poles secured to said block of non-magnetic material and having portions overlapping and secured on the sides of said block, and stub shafts therefor in alignment with each other, together with an armature structure embracing said rotor and normally stationary with respect thereto.

16. A magneto electric machine comprising a U-shaped permanent magnet, a rotor 130

journalled in end-wise position between said field poles and on an axis passing through said field poles, said field poles having apertures to accommodate said axis, and an armature structure including a pair of pole shoes, a frame of non-magnetic material spacing said pole shoes apart, and end plates of magnetic material supporting said frame from the axis of said rotor lying between the said rotor and the poles of said magnet respectively and having laterally projecting bearing sleeves extending through said apertures concentrically with the axis of said rotor.

17. A magneto electric machine comprising a U-shaped permanent magnet, a rotor journalled in endwise position between said field poles and on an axis passing through said field poles, said field poles having apertures to accommodate said axis, and an armature structure including a pair of pole shoes, a frame of non-magnetic material spacing said pole shoes apart, and end plates of magnetic material supporting said frame on the axis of said rotor, lying between said rotor and the poles of said magnet respectively and having laterally projecting bearing sleeves extending through said apertures concentrically with the axis of said rotor, said rotor comprising magnetically separated elements of magnetic material having permanent magnetic contact with said magnet poles through said end plates.

18. A magneto electric machine comprising a U-shaped permanent magnet, a rotor journalled on an axis transverse to the poles thereof and having inductor poles in permanent magnetic relation each with one pole of said magnet, an armature structure in juxtaposition to said rotor and adjustable about the axis thereof, and a contact device on the exterior of one pole of said magnet and connected rigidly with said armature structure for adjustment therewith, together with means driven from the axis of the rotor for operating said interrupter.

19. A magneto electric machine comprising a base of non-magnetic material, upright projections from said base provided with internal shoulders, a vertically disposed U-shaped permanent magnet seated on said base against said shoulders and embraced by said projections, an armature structure mounted on an axis transversely of the embraced field poles and having projecting bearings which extend through apertures therein, and a rotor embraced by said field poles between said projecting bearings in an end-wise position on an axis concentric therewith, and having inductor poles respectively in permanent magnetic contact each with a different pole of said field magnet.

20. A magneto electric machine comprising a base of non-magnetic material having

up-standing projections, a pair of U-shaped permanent magnets arranged side by side with their poles meeting said projections, registering semi-circular apertures in the poles thereof formed on a transverse axis 70 lying in the plane between the poles, a rotor journalled in said apertures in an end-wise position between said field poles, an armature structure in juxtaposition to said rotor, and means connecting said magnets to the 75 said up-standing projections of the base in the relation set forth.

21. A magneto electric machine comprising a base of non-magnetic material having up-standing projections, a pair of U-shaped 80 permanent magnets arranged side by side with their poles meeting said projections, registering semi-circular apertures in the poles thereof formed on a transverse axis 85 lying in the plane between the poles, and a 90 rotor journalled through said apertures on said axis in an end-wise position between said field poles.

22. A magneto electric machine comprising a base having up-standing projections, 90 bearing apertures in said projections, a pair of U-shaped permanent magnets arranged side by side and meeting said projections and having registering semi-circular apertures formed on an axis lying in the plane 95 between the poles and coinciding with the axis of the apertures in said up-standing projections, a rotor embraced by said field poles in an end-wise position and journalled on the aforesaid axis, said rotor being 100 formed in two separable halves transversely rigidly connected together, and means securing said field magnets together about the axis of said rotor, and also securing them to said up-standing projections of the base. 105

23. A magneto electric machine comprising a field structure having rotatable poles, a normally stationary armature structure adjustable angularly about the axis of said field poles and a condenser supported upon 110 and movable with said armature structure and having electrical connection with the windings thereof.

24. A magneto electric machine comprising a field structure having rotatable poles, 115 a normally stationary armature structure angularly adjustable about the axis of said field poles and having a generating winding, a condenser supported from said structure and having electrical connections with the generating winding thereof, and interrupter contacts operated by the rotation of said field poles and connected to said armature structure for angular adjustment therewith. 120

25. A magneto electric machine comprising relatively rotatable field and armature members, said armature structure including the usual generating winding, a circuit interrupter having connection with and controlling said generating winding, and means 125 130

for operating said circuit interrupter from the rotatable one of said members comprising a cam driven from said member and a radially movable ball retained in position to be engaged by said cam and bearing upon the movable element of said interrupter.

26. A magneto electric machine comprising relatively rotatable field and armature structures, said armature structure including the usual generating winding, a circuit interrupter connected with and controlling said winding and means for operating said circuit interrupter comprising a cam driven by the rotatable one of said members, and a radially movable ball held in fixed angular position between said cam and a movable element of said interrupter.

27. In a magneto electric machine, a field structure having rotatable poles, a normally stationary armature structure adjustable about the axis of said field poles, said armature structure including the usual generating winding, interrupter contacts and a supporting frame therefor rigidly connected with said armature structure for adjustment therewith and having electrical connection with said generating winding, and means to operate said interrupter comprising a cam driven from said rotatable field poles, and a ball carried in a socket in the frame of said interrupter between said cam and a movable element of the interrupter.

28. A magneto electric machine comprising a base of non-magnetic material, upstanding projections on said base having transversely alined journals therein, a rotor mounted in said journals in an end-wise position and a U-shaped permanent magnet supported from said base, embracing said rotor and having apertures in its poles through which the shaft of said rotor passes without contact with the walls thereof.

29. A magneto electric machine comprising a base of non-magnetic material, upstanding projections thereon, a U-shaped permanent magnet the poles of which overlap said projections and are fixed in transverse position as respects said base thereby, a rotor journaled on an axis transversely of said overlapping parts in an end-wise position between said field poles and comprising inductor elements in permanent magnetic contact each with one of said field poles, and an armature structure in juxtaposition to said rotor.

30. A magneto electric machine comprising a base of non-magnetic material, upstanding projections therefrom, a U-shaped permanent magnet the poles of which overlap said projections and are fixed in transverse position as respects said base thereby, a rotor journaled on an axis transversely of said overlapping parts in an end-wise position between said field poles, and an armature structure comprising a pair of pole

shoes mounted in juxtaposition to said rotor, a frame of non-magnetic material interconnecting said shoes, and a pair of end plates journaled on the axis of said rotor and lying intermediate the ends of said rotor and the inner cheeks of said field poles, but in permanent magnetic contact therewith.

31. A magneto electric machine comprising a field structure having rotatable inductor poles of permanent and opposite magnetic polarity, the main body of said field structure being normally stationary, and an armature structure mounted in juxtaposition to said rotatable field poles and adjustable bodily in angular relation with respect thereto, said armature structure comprising a pair of spaced armature pole shoes, a frame of non-magnetic material rigidly connecting the same together at their lower ends, a core of magnetic material connecting the same together at their upper ends, an armature winding carried by said core, and end plates of magnetic material by which said frames are supported upon the axis of said rotatable field poles for adjustment thereabout, and through which flux is conducted from the normally stationary part of said field structure to the rotatable poles thereof.

32. A magneto electric machine comprising a field structure having rotatable inductor poles of permanent and opposite magnetic polarity, the main body of said field structure being stationary, a shaft of non-magnetic material on which said rotatable poles are journaled, and an armature structure mounted in juxtaposition to said rotatable field poles and comprising a pair of spaced pole shoes, a circular frame work of non-magnetic material fixing said shoes together and spacing the same apart at their inner ends, a core of magnetic material connecting pole shoes at their upper ends, an armature winding carried by said core, and magnetic end plates connected with said framework having laterally projecting bearing sleeves journaled on the aforesaid shaft and by means of which said armature structure is supported upon said shaft, the flux from the fixed portion of said field structure being conducted to the rotatable poles thereof through said end plates.

33. A magneto electric machine comprising a base of non-magnetic material, abutments formed on the upper face of said base, a pair of U-shaped permanent magnets forming a field structure and positioned together on said base by said abutments, registering semi-circular apertures formed on a traverse axis on adjoining sides of said field magnets, a rotatable inductor journaled in said apertures, an armature structure mounted in co-operative relation thereto and securing said permanent magnets to said base.

34. A magneto electric machine compris-

- 5 ing a pair of U-shaped permanent magnets having registering semi-circular apertures on their adjoining sides formed on a common transverse axis, a rotatable inductor journalized through said apertures, means securing said pair of permanent magnets together and about the said rotatable inductor, and an armature structure in juxtaposition to said inductor.
- 10 35. A magneto electric machine comprising a pair of U-shaped permanent magnets placed side by side and having registering semi-circular apertures formed in each pole thereof on the adjoining sides and on a common transversely extending axis, and relatively movable inductor and armature members journalized through said apertures, together with means securing said pair of field magnets together.
- 15 36. A magneto electric machine comprising a pair of U-shaped permanent magnets, which are provided with registering semi-circular apertures on the adjoining sides of each pole thereof on a common transverse axis, an armature structure embraced by said magnets and journalized in said apertures, and a rotatable inductor journalized within the armature structure on a shaft having bearings lying within said apertures.
- 20 37. A magneto electric machine comprising a permanent field magnet structure, and a normally stationary, but adjustable armature structure embraced by said field poles and journalized in apertures in the poles thereof, end projections from the journals of said armature structure projecting without said field structure, and circuit controlling apparatus carried by one of said end projections, together with a rotatable induc-
- 25 30 35 40 45 50 55 60 65 70 75 80 85 90 95 100
- tor journalized concentrically with said armature structure, and having a shaft one end of which projects without said field structure and is provided with a cam to operate said circuit controlling apparatus.
38. A magneto electric machine comprising a permanent field magnet structure, an armature structure embraced by said field poles and having angularly adjustable portions which are journalized in and project from the exterior of, the pole of said field magnet structure, circuit controlling apparatus carried on one of said projections and a rotatable inductor having an exteriorly located cam on one end adapted to operate said circuit controlling apparatus.
39. A magneto electric machine comprising a permanent field magnet structure, a rotatable inductor embraced in an end-wise position between and journalized on an axis extending transversely of the poles of said structure, an armature structure also embraced by said field magnets, a circuit controlling apparatus on the exterior of said field structure, an exteriorly located cam carried by said inductor and operating said circuit controlling apparatus and connections between said circuit controlling apparatus and said armature structure whereby said apparatus is shifted when the armature structure is shifted to vary the timing of the device.

In testimony whereof I hereunto affix my signature in the presence of two witnesses.

CHARLES THOMAS MASON.
